SCUBA DIVER'S BOARD

William Barkley, 3847 Underwood Drive, 3,
San Jose, Calif. 95117

Filed Apr. 15, 1971, Ser. No. 134,545

Term of patent 14 years

Int. Cl. D12—06

U.S. Cl. D71—1 CC

FIG. 1.

FIG. 2.

FIG. 3.

FIG. 4.

FIG. 5.

FIG. 1 is a perspective of a scuba diver's board showing my new design.

FIG. 2 is a top plan view thereof with the bottom being identical to the top.

FIG. 3 is a side elevation thereof with the opposite side being identical to the side shown.

FIG. 4 is a rear end elevation thereof.

FIG. 5 is a front end elevation thereof.

I claim:

The ornamental design for a scuba diver's board, as shown and described.
